DESIGN FOR A FRAME FOR COMBINATION BREAD SLICING AND WRAPPING MA- CHINES

Israel C. Gellman, Rock Island, Ill.

Application August 29, 1936, Serial No. 64,641

Term of patent 7 years

To all whom it may concern:

Be it known that I, Israel C. Gellman, a citizen of the United States and a resident of Rock Island, in the county of Rock Island and State of Illinois, have invented a new, original, and ornamental Design for a Frame for Combination Bread Slicing and Wrapping Machines, of which the following is a specification, reference being had to the accompanying drawing, forming a part thereof, and in which:

The figure is a perspective view of a frame for combination bread slicing and wrapping machines showing my new design, the opposite side of the machine being identical in appearance with the side shown in the figure.

I claim:

The ornamental design for a frame for combination bread slicing and wrapping machines, as shown and described.

ISRAEL C. GELLMAN.
